HIS ATTORNEY

UNITED STATES PATENT OFFICE.

JAMES W. LOY, OF BURNETT, CALIFORNIA, ASSIGNOR OF ONE-HALF TO F. M. FISHBACK, OF LONG BEACH, CALIFORNIA.

TOOL FOR REMOVING CASING FROM WELLS.

Application filed February 12, 1923. Serial No. 618,699.

To all whom it may concern:

Be it known that I, JAMES W. LOY, a citizen of the United States, residing in Burnett, Los Angeles County, California, have invented certain Improvements in Tools for Removing Casing from Wells, of which the following is a specification.

My invention relates more particularly to a tool adapted for use in gripping and turning the sections of a casing or drill pipe for the purpose of removing it from a well, and one of the principal objects of my invention is to provide a tool which has one part adapted to be connected to and operated by the drill pipe, in the same rotary direction therewith, and another part adapted to engage with the pipe or casing to be removed, but to turn in the opposite direction, whereby to unscrew the same. Or to state the main object in another way, one part of the tool is driven in one direction, while the part which grips the pipe or casing to be removed is driven in the opposite direction. Thus the tool can be used with the usual rotary table used for turning the drill pipe and without reversing the direction of rotation of the rotary table or drill pipe, it will unscrew the pipe or casing to which said tool is attached.

Other objects and advantages will be apparent from the following description of one practical embodiment of the invention, taken in connection with the accompanying sheet of drawings, in which,—

Figure 1 is a vertical sectional view of the embodiment of the invention used for illustrative purposes;

Figures 2, 3, 4 and 5, are cross sectional views taken on the lines, 2—2, 3—3, 4—4 and 5—5, of Fig. 1; and

Figure 6 is a fragmentary sectional view of a modified form of the lower portion of the tool adapted for gripping the inside of a casing instead of the outside of a drill pipe shown in Fig. 1.

Referring in detail to the drawings, 1 designates a well casing, and 2, a section of drill pipe which it is desired to remove from the well, while 3 designates the operating drill pipe operated from the rotary table (not shown) in the usual manner. My tool is attached to and operated by said drill pipe

3. The tool as here illustrated comprises a coupling 4, screwed on to the lower end of the pipe 3, and having screwed into its lower

end a member 5, provided with an annular flange 5^a, with a central bore, 5^b, substantially as shown. A bushing like member 6, fits over the coupling 4, with packing 7, between said coupling and bushing. A collar 8, around said coupling, is secured to said bushing 6, by means of screws 9, and holds said packing in place. A sleeve or casing member 10, at its upper end, screws on to said bushing 6, substantially in the manner indicated, and is provided with an inner annular shoulder, 10^a, to receive therein a disc member 11, interlocked with said sleeve or casing 10, in the manner indicated in Fig. 3, whereby to turn with said member 10. The lower end of the member 5, is provided with gear teeth, 5^c, extending longitudinally thereof, as indicated in Figs. 1 and 4, which mesh with long gears, 12, mounted on the pins, 13, the upper ends of which are connected in the disc member 11, and the lower ends of which are anchored in the inner flange 10^b of the sleeve or casing member 10, substantially as shown. The lower end of the member 5, is reduced, as at 5^d, and is also anchored in the lower end of the member 10^b with packing 14, held in place by a plate 15, substantially as shown.

Screwed into the lower end of said sleeve or casing member 10, as at 10', is an extension member 16, having at its lower end an inner beveled part, 16^a. Pivotally mounted in said extension 16 are four lever members, 17, 17, the upper ends of which are provided with teeth, 17^a, and the lower ends of which are provided with bearing sockets, as 17^b, to pivotally receive and hold dogs 18, adapted to bite into the pipe 2, substantially as shown. The lower ends of the levers 17 have a sliding connection with said dogs 18 so that when the extension 16 and the levers 17 are turned circumferentially, said levers are forced out by a cam action on the dogs 18 which tends to force the lower ends of said levers 17 outwardly, thus forcing the upper ends of the levers and their teeth 17^a into the pipe 2, and at the same time force the dogs 18 into the pipe 2, so as to turn said pipe with said extension 16 and levers 17. The connections between the lower ends of the levers 17 and said dogs 18 are eccentric, as indicated in Fig. 5, the rounded part, 18', of each dog 18, being eccentrically formed relative to said dog.

It will be understood from the construc-

tion thus far described, that the parts 4, 5, 5^a and 5^c turn with the drill pipe 3, and that by reason of the gear portion 5^c being in mesh with the gears 12, which are in turn 5 in mesh with the gear teeth 10^c of the member 10, said member 10, and the parts 6, 8, above, and the parts 11, 12, 16, 17 and 18, all turn in the opposite direction, thus turning the drill pipe 2 in a direction to unscrew 10 it from the section below, assuming that it is connected with a right hand screw. In other words, when the upper parts are turned in the direction, as they normally are, to screw pipe sections having right hand 15 threads together, the lower part of said tool and its connections to the pipe 2, turn in the opposite direction and unscrew the pipe 2, whereupon it can be withdrawn with the tool from the well. The reversal mechanism 20 will be understood from Fig. 4.

Referring now to Fig. 6, the lower part 25 of the tool is constructed to engage the inside of a casing, as 2^a, instead of the outside, for the purpose of turning it to unscrew it from the next section. A member 20, takes the plate of the extension 16, and is screwed into the lower end of the member 10, and is provided with longitudinally extending 30 channels, 20^a, to receive the lever members 21, 21, similar to the levers 17, and pivoted to said member 20, substantially as shown. The dogs, 22, are similar to the dogs 18, and when the parts 20 and 21 are turned relative to the dogs 22, said dogs are forced out as 35 the lower ends of the levers 21 are forced inwardly and the upper ends of said levers 21 are forced outwardly into biting engagement with the inside of the pipe 2^a, thus turning said pipe 2^a with all of said parts 40 and unscrewing it from the section below.

Thus I have described a practical tool for use with the standard well equipment, which can be connected to drill pipe and operated thereby for the purpose of turning another 45 section of pipe, or casing in a removal direction, and while I have shown and described one embodiment of the invention, I am aware that many changes in details can be made without departing from the spirit 50 of the invention, and I do not limit the invention to the details shown, except as I may be limited by the hereto appended claims.

I claim:

1. In a tool of the character referred to, 55 a part adapted to be turned in one direction, a part adapted to be turned relative to said first part, reversal transmission mechanism between said parts adapted when said first part is turned in one direction to turn 60 the other part in the opposite direction, said second part being open to receive an object inserted therein, and gripping means in said second part adapted to be closed upon said object to turn it therewith.

2. In a tool of the character referred to,

a part adapted to be turned in one direction, a second part connected therewith and adapted to be turned relative thereto, reversal transmission mechanism between said parts to cause one part to turn in the opposite direction when the other part is turned, gripping means in said second part adapted to engage and grip an object inserted therein, and means causing said gripping means to function when said second part is turned in one direction whereby to grip and turn said object therewith. 70

3. In a tool of the character described, a part adapted to be connected to and turned by means of a driving member, a second part connected therewith and adapted to turn relative thereto, a planetary gear transmission interposed between said parts for reversing the direction of one part relative to the other and gripping means in said second part adapted to be operated to grip an object inserted therein as said second part is turned, whereby to turn said object therewith, substantially as described. 80

4. In a tool of the character described, 90 a part adapted to be turned in one direction, a second part connected therewith and adapted to turn relative thereto, a reversal transmission mechanism interposed between said parts for turning one part in one direction when the other part is turned in the opposite direction, said second part being adapted to have telescopic relationship with an object to be turned, and gripping means carried by said second part and adapted to be actuated into gripping engagement with said object when said second part is turned relative thereto, whereby to turn said object. 100

5. In a tool of the character described, 105 a part adapted to be turned about its axis, a second part connected therewith and adapted to be turned relative thereto, a planetary gear transmission interposed between said parts for reversing the direction of one part relative to the other part when one part is rotated, said second part being adapted to have telescopic relationship with an object to be gripped and turned therewith, and gripping means carried by said second part and adapted to be actuated into gripping engagement with said object when turned relative thereto, whereby to grip said object and turn it therewith. 110

6. In a device of the character referred to, 120 in combination, a central member having a gear portion, an outer member to turn thereon and having a plurality of gears in mesh with the gear portion of said central member and constituting a reversal transmission from said central member to said outer member, said outer member being adapted at its lower end to telescope with another object to be turned therewith, gripping means carried by said outer member, and means actuated by the turning of said outer member 125

relative to said object for causing said gripping means to function and to grip said object and to turn it therewith.

7. In a device of the character referred to, 5 in combination, a central member having a gear portion and adapted to be connected to a driving member for rotating the same, an outer member over said central member, a plurality of gears interposed between said 10 outer member and the gear portion of said central member and in mesh therewith and constituting a reversal transmission between said central and outer members, a plurality of gripping members carried by said outer 15 member and adapted to be actuated to grip another object in telescopic relationship therewith, and means for actuating said

gripping members into gripping engagement with said object as said outer member is turned relative to said object. 20

8. In a tool of the character referred to, a part adapted to have telescopic relationship with another object, gripping members carried by said part to grip said object, and means for causing said gripping members 25 to operate and grip said object as said part is turned relative thereto.

Signed at Los Angeles, Los Angeles County, California, this 7th day of February, 1923.

JAMES W. LOY.
